UNITED STATES PATENT OFFICE.

SERGIUS P. KHATUNZEFF, OF BRIDGEPORT, CONNECTICUT.

PAPER FASTENER.

Application filed November 18, 1925. Serial No. 69,786.

This invention relates to a paper fastener adapted to the purpose of securing together either the corners or side edges of a plurality of sheets of paper or the like.

Objects of the invention are to provide a simple, inexpensive and practical paper fastener which will be very efficient in use to hold together sheets of paper or the like; which can be readily applied to material to be fastened and just as readily removed from the material; which will in no manner mar papers or the like secured together; and which will be capable of long and repeated use, no folding or excessive bending operation tending to weaken the material of which the fastener is composed being necessary to make application of the fastener to papers or the like to be secured together.

With the above objects in view, as well as others which will appear as the specification proceeds, the invention comprises the construction, arrangement and combination of parts as now to be fully described and as hereinafter to be specifically claimed, it being understood that the disclosure herein is merely illustrative, changes in details of construction and arrangement of parts being permissible so long as within the spirit of the invention and the scope of the appended claims.

In the accompanying drawing forming a part of this specification,

Fig. 1 is a plan view of a paper fastener having the features of the invention;

Fig. 2 is a plan view disclosing the first step in securing together at one corner a plurality of sheets of paper;

Fig. 3 is a plan view disclosing the second step in securing together the plurality of sheets;

Fig. 4 is a plan view disclosing the third or final step in securing the sheets;

Fig. 5 is a view similar to Fig. 4 disclosing the fastener associated with a plurality of sheets of paper to secure their side edges together;

Fig. 6 is a plan view of a paper fastener of modified construction and having the features of the invention;

Fig. 7 is a plan view disclosing the first step in securing together at a side edge a plurality of sheets of paper;

Fig. 8 is a plan view disclosing the second step in so securing together the plurality of sheets;

Fig. 9 is a plan view disclosing the third or final step in so securing the sheets; and

Fig. 10 is a view similar to Fig. 9 disclosing the fastener of Figs. 6 to 9 associated with a plurality of sheets of paper to secure their corners together.

Referring more particularly to Figs. 1 to 5, the fastener there shown consists of a flat blank 10 of suitable material, as, for example, metal or celluloid, including a pair 65 of portions, denoted 11 and 12, respectively, connected by a neck 13. The portion 11 includes tongues 14 and 15 at right-angles to each other and spaced preferably at equal distances from opposite sides of the neck 13. The portion 12 includes tongues 16 and 17 which extend inwardly of the blank, the tongue 16 being between the tongue 14 and the neck 13, and the tongue 17 being between the tongue 15 and the neck 13. The 70 blank 10 is rectangular or square in general outline, and the tongues 16 and 17 include inward pointed edges 18 and 19 situated adjacent the angles between the tongues 14 and 15, respectively, and the neck 13.

The fastener of Figs. 1 to 5 is more especially adapted for use at a corner of papers or the like to be fastened together, although it could readily be used at the side edge of papers or the like.

The manner of application of the fastener to a corner of papers to be secured together will be apparent from Figs. 2, 3, and 4. As disclosed in Fig. 2, A represents a plurality of sheets of paper a corner of each of which has been inserted above the portion 11, its tongues 14 and 15 and the neck 13, and beneath the tongues 16 and 17 of the portion 12 of the fastener, the inner edges 20 and 21 of the slots between the neck 13 and the tongues 16 and 17 causing the side edges B and C of each sheet to terminate at the bases 22 and 23, respectively, of the

tongues 16 and 17. At this time the outer end portions of the tongues 14 and 15 and the whole of the portion 12 are without the confines of the sheets of paper.

In Fig. 3 the sheets of paper are shown as having been folded along the line D which is oblique to the side edges B and C and is defined by the edges 18 and 19 of the tongues 16 and 17. In said Fig. 3, no part of the blank 10 is below the sheets of paper or the like, the tongues 16 and 17 being inserted between the uppermost sheet and the folded over part E thereof.

In Fig. 4 the tongues 14 and 15 are shown as having been sprung about the side edges B and C of the sheets of paper, so that now the portion 11 is at a corner of the sheets adjacent the line of fold D, the neck 13 and the portion 12 are upon the upper side of the sheets, the tongues 16 and 17 are inserted between the uppermost sheet and the folded over part E thereof, and the tongues 14 and 15 are upon the lower side of the sheets. Thus the sheets are securely locked between the neck 13, the tongues 16 and 17, and the tongues 14 and 15, and cannot be accidentally removed from the paper fastener. To withdraw the fastener from the sheets, the tongues 14 and 15 must first be sprung from their locations beneath the paper as disclosed in Fig. 4, and the paper must afterwards be folded back from its position of Fig. 3 to its position of Fig. 2. It is apparent that the tongues 14 and 15 preclude the possibility of folding of the paper from the position of Fig. 3 to that of Fig. 2 when said tongues 14 and 15 are situated as in Fig. 4.

Referring more particularly to Figs. 6 to 10, the fastener there shown consists of a flat blank 10' including a pair of portions 11' and 12' connected by a neck 13'. The portion 11' includes tongues 14' and 15' which are parallel with each other and are at right-angles to the portion 11', and are spaced preferably at equal distances from opposite sides of the neck 13'. The portion 12' includes tongues 16' and 17' which are parallel with each other and with the tongues 14' and 15' and extend inwardly of the blank, the tongue 16' being between the tongue 14' and the neck 13', and the tongue 17' being between the tongue 15' and the neck 13'. The blank 10' is also rectangular or square in general outline. The inner edges 18' and 19' are situated adjacent the inner edge of the portion 11' and are desirably flat.

The fastener of Figs. 6 to 10 is more especially adapted for use at a side edge of papers or the like to be fastened together, although it could readily be used at the corner of papers or the like.

The manner of application of the fastener

of Figs. 6 to 10 to a side edge of papers to be secured together will be apparent from Figs. 7, 8, and 9. As disclosed in Fig. 7, A' represents a plurality of sheets of paper a side edge of each of which has been inserted above the portion 11', its tongues 14' and 15' and the neck 13', and beneath the tongues 16' and 17' of the portion 12' of the fastener, the inner edges 20' and 21' of the slots between the neck 13' and the tongues 16' and 17' causing the edges B' of the sheets to terminate at the bases 22' and 23', respectively, of the tongues 16' and 17'. At this time the outer end portions of the tongues 14' and 15' and the whole of the portion 12' are without the confines of the sheets of paper.

In Fig. 8 the sheets of paper are shown as having been folded along the line D' which is parallel with the side edge B' and is defined by the flat edges 18' and 19' of the tongues 16' and 17'. In said Fig. 8, no part of the blank 10' is below the sheets of paper, the tongues 16' and 17' being inserted between the uppermost sheet and the part E' thereof.

In Fig. 9 the tongues 14' and 15' are shown as having been sprung about the side edges B' of the sheets of paper, so that the portion 11' is at a side of the sheets adjacent the line of fold D', the neck 13' and the portion 12' are upon the upper side of the sheets, the tongues 16' and 17' are inserted between the uppermost sheet and the folded over part E' thereof, and the tongues 14' and 15' are upon the lower side of the sheets. The sheets are locked between the neck 13', the tongues 16' and 17', and the tongues 14' and 15'. The fastener is withdrawn from the sheets in the manner described in connection with Figs. 2 to 4.

In Fig. 5, I have disclosed the paper fastener of Fig. 1 applied to a side edge of sheets of paper, and Fig. 10 the fastener of Fig. 6 is shown applied to the corner of sheets. The manner of application is apparent from the description already given.

The opening 24 in the portion 11 and the opening 24' in the portion 11' is for the purpose of filing or suspending papers or the like secured by my novel fastener.

It will be evident that various embodiments of the invention will suggest themselves to those skilled in the art of making paper fasteners without departing from the principle of the present invention.

Having thus fully described the invention, what I claim as new and desire to secure by Letters Patent is:

1. A paper fastener comprising a plurality of portions and a neck connecting said portions, one of said portions having tongues at opposite sides of said neck and spaced therefrom, and the other of said por-

tions having tongues adjacent said neck and between said neck and the tongues first mentioned.

2. A paper fastener comprising a flat blank including a pair of bodies and a neck connecting said bodies, one of said bodies having tongues at opposite sides of and spaced from said neck, and the other body

having tongues at opposite sides of said neck and between said neck and the tongues 10 first mentioned.

Signed at Bridgeport, in the county of Fairfield and State of Connecticut, this 16th day of November A. D., 1925.

SERGIUS P. KHATUNZEFF.
